UNITED STATES PATENT OFFICE

CLIFTON P. HOWARD, OF WORCESTER, MASSACHUSETTS, ASSIGNOR TO ROCKWOOD SPRINKLER COMPANY OF MASSACHUSETTS, OF WORCESTER, MASSACHUSETTS, A CORPORATION OF MASSACHUSETTS

RESTRICTED ORIFICE DEVICE

Application filed November 16, 1931. Serial No. 575,357.

This invention relates to devices through which a restricted flow of air or gas is permitted between different pressure areas. Such devices are commonly used where a retarded equalization of pressure is desired after a change in pressure at one side of the orifice device.

One instance of such use is in certain types of air exhausters for dry pipe sprinkler systems. In such exhausters, an air pressure chamber is provided which has no outlet except through a restricted orifice and in which the air is normally maintained at dry pipe pressure. When a sprinkler head opens, the dry pipe pressure drops quickly, while the pressure in the closed chamber drops much more slowly, due to the restricted orifice through which the air must escape.

The differential pressure thus developed is utilized to open a large vent valve through which the remaining air in the dry pipe system may be quickly discharged. Orifice devices of different kinds have been tried in such air exhausters but much difficulty has been encountered, due to the clogging of the orifices by dust or dirt. Fine strainers have been provided to protect the orifice but these strainers also fill up and become clogged in course of time.

It is the object of my invention to provide an improved orifice device for such purposes, so designed that it may be easily and cheaply constructed and that it will be relatively free from the difficulty of clogging.

A further object is to provide a construction in which two orifice members in series produce the restrictive effect of a single orifice of substantially less diameter.

My invention further relates to arrangements and combinations of parts which will be hereinafter described and more particularly pointed out in the appended claims.

A preferred form of the invention is shown in the drawing, in which

Fig. 1 is a sectional side elevation of portions of an air-exhauster having my invention embodied therein;

Fig. 2 is a sectional side elevation of my improved orifice device;

Fig. 3 is a sectional side elevation of one of the orifice members;

Fig. 4 is an end elevation thereof, looking in the direction of the arrow 4 in Fig. 3;

Fig. 5 is a view similar to Fig. 3 but showing a slight modification, and

Fig. 6 is a sectional elevation showing a further modification.

Referring to Fig. 1, I have shown a portion of an air exhauster including a pressure chamber 10, a chamber 11 freely connected to the dry pipe system, a partition 12 separating the chambers 10 and 11 and having an opening 13 therethrough, a diaphragm 14 extending across the chamber 11 below the partition 12, and a member 15 extending through an opening in the center of the diaphragm 14 and securely clamped thereto by a nut 16. The member 15 and nut 16 extend freely upward through the opening 13, leaving a substantial air passage around the nut 16, so that the air under pressure in the chamber 10 has direct access to the upper side of the diaphragm 14.

My improved orifice device D is mounted in a threaded opening 17 in the upper part of the member 15, which opening 17 is connected by a passage 18 to the chamber 11. With this construction it will be seen that the only communication between the chambers 10 and 11 is through the orifice device D and the passage 18. This general construction is typical of certain commercial air exhausters and in itself forms no part of my present invention, which relates particularly to the orifice device D.

The orifice device D in its preferred form comprises a holder 20 having an end portion 21 to which a wrench may be applied and having a hub portion 22 which is externally threaded to engage the threaded opening 17 in the member 15. The member 20 is also provided with an axial passage 24, an annular shoulder 25, an internally threaded portion 26, and an enlarged end recess 27.

Orifice members 30 are mounted in the passage 24 and in a corresponding passage 31 in a clamping screw 32, which is threaded into the portion 26 of the holder 20. The en-

larged head of the screw 32 is received in the enlarged recess 27.

The orifice members 30 are provided with end flanges 35 which are clamped against the 5 shoulder 25 by the clamping screw 32, by which means the orifice members are securely held in the holder 20. Each orifice member 30 is also provided with a conical portion 37 projected out of the plane of the flange 35 10 and having a restricted orifice 40 extending through the extreme pointed end of the conical portion 37.

In the preferred form, the member 30 is of hollow construction, with the flange 35 15 and conical portion 37 all formed of suitable and relatively thin metal.

While a single one of the orifice members 30 may be used in the holder 20, I prefer to use these orifice members in pairs, as shown 20 in Fig. 2, as improved results are attained by thus combining two of the members 30.

I have found by experiment that the provision of the orifice 40 at the extreme end of a conical portion, as 37, largely does away with 25 the liability to clogging by small particles of dust or dirt, and that the orifice is very much less liable to clog than is the case where the orifice is made in a flat metal disc, as has been previously the custom. In fact, the substitution of my improved orifice member or 30 members for the perforated flat metal disc has enabled me to do away entirely with the fine mesh strainers which have been previously used in such devices.

35 Furthermore, I have found that a pair of my improved orifice members, oppositely disposed as shown in Fig. 2, will have the same restricting effect as a single perforated disc having a substantially smaller orifice. For 40 example, the use of two of my improved orifice members with openings of .010" in diameter will produce the same restricting effect as a single plate having an opening of .007" in diameter. Obviously, the larger 45 openings are easier to form accurately and are less liable to clogging than the smaller opening required to produce the same effect in a single flat plate.

If for any reason my improved orifice 50 members require renewal, the removal and replacement of these members may be effected by any mechanic without special skill or experience, whereas with the previous construction a relatively large unit was necessarily replaced.

In the construction shown in Fig. 5, the 55 walls of the orifice member 50 is provided with side walls which are gradually reduced 60 in thickness toward the perforated outer end or point, thus presenting a very thin or knife edge effect around the orifice.

In Fig. 6, I have shown the two orifice members, as 30 or 50, secured together by 65 crimping one flange 55 around the other

flange 56, thus preventing separation of the pair of orifice members.

Having thus described my invention and the advantages thereof, I do not wish to be limited to the details herein disclosed, otherwise than as set forth in the claims, but what I claim is:—

1. A device for effecting very slow air flow 70 between chambers containing air at substantially different pressures which comprises a holder having an axial opening therethrough, a pair of orifice members reversely mounted within said holder and in said opening and each having an outwardly extended and substantially conical portion with a greatly restricted perforation through its extreme outer pointed end, and means to hold said members reversely mounted in said holder.

2. A device for effecting very slow air flow 75 between chambers containing air at substantially different pressures which comprises a holder having an axial opening therethrough, a pair of orifice members reversely mounted within said holder and in said opening and each having an end flange and an outwardly extended and substantially conical portion with a greatly restricted perforation through its extreme outer pointed end, and means to hold said members reversely mounted in said holder with said end flanges 80 firmly engaging each other and firmly seated in said holder.

In testimony whereof I have hereunto affixed my signature.

CLIFTON P. HOWARD.
